MACHINE FOR OPERATING UPON
SHOE PARTSErastus E. Winkley, Lynn, Mass., assignor to
United Shoe Machinery Corporation, Paterson,
N. J., a corporation of New Jersey

Application December 21, 1933, Serial No. 703,449

20 Claims. (Cl. 12—17)

This invention relates to a machine for operating upon shoe parts and is herein illustrated as embodied in a machine for operating upon the margins of shoe soles. As shown, the machine applies a coating to the margin of a sole.

Many shoe parts having irregular or curved contours are operated upon around part or the whole of their peripheries to prepare them for embodiment in the shoe. Instances of such operations are to be found in the skiving of the margins of box toes and counters, the edging of toe caps, the coating of heel lifts, and the fitting of shoe soles by channeling, roughing, coating or otherwise acting upon the margin of the soles. Such operations can be carried out very much more expeditiously if the machine to which the parts are presented is arranged so as to feed the margin of the work automatically past the operating tool or tools, maintaining the edge of the part in contact with a suitable gage during such traversing movement.

Accordingly, an important object of the invention is to provide a machine for operating upon shoe parts having improved means for moving the shoe part past a tool without interfering with the guiding of the work.

Features of the invention are to be found in an improved feeding mechanism which not only effects a feeding movement of the work without interfering with the guiding of the work, but which, as illustrated, is arranged to impart to the work a force acting in a direction laterally of the direction of progress of the work. As illustrated, the machine is arranged to apply this force impositively to maintain the work in contact with an edge gage.

These and other features of the invention will now be set forth in the following specification taken in connection with the accompanying drawings, in which

Fig. 1 is an end elevation of the machine with parts broken away;

Fig. 2 is a plan view with the upper part of the machine removed;

Fig. 3 is a detailed perspective view of the members which act upon the work to urge it toward the edge gage;

Fig. 4 is a vertical section on the line IV—IV of Fig. 2;

Fig. 5 is a detailed perspective view of the feeding members which engage the under side of the work;

Fig. 6 is a plan view, with parts broken away and in section, of the driving mechanism for the

feeding members which engage the upper side of the work; and

Fig. 7 is a section on the line VII—VII of Fig. 6.

The machine is built up around a box-like frame 10 having a removable cover portion 12 bolted thereto. Supported in brackets formed on this cover portion 12 at the rear of the machine is a drive shaft 14 supplied with power from any suitable source, not shown, and at the top of the machine is a cross shaft 16 connected to the drive shaft 14 by a chain 18 running upon suitable sprockets and passing under an idler sprocket 20. Extending transversely of the frame 10 parallel to and beneath the shaft 16 is a cam shaft 22 which receives power from the cross shaft 16 through a vertical shaft 24 connected to the shafts 16 and 22 by miter gears 26 and 28 (Fig. 1).

The machine as here shown is operating upon a shoe sole S, which has been previously cemented for use in a compo shoe, and is applying a coating of solvent to the cemented area which is on the flesh side, here shown as beneath. This use of the machine for applying a coating to the work is purely illustrative and it will be understood that the machine may be adapted for many other uses and for use in connection with many other types of work. For this particular operation, however, the machine has a receptacle 30 which is bolted to the front of the frame 10.

Brushes 32 and 34, which are shaped as shown in Fig. 2 and are secured to carriers 35, are mounted for vertical reciprocation upon guide rods 36 into and out of coating material contained within the receptacle and into contact with the lower face of the work. The size of the brushes and their rate of reciprocation is so related to the rate of feeding movement of the work that the applied splotches of coating material overlap somewhat. Two of these rods 36 are provided which are held in sockets 38 at the bottom of the receptacle by means of clamp screws 40 and the upper ends of the rods are secured in spaced relation in a manner to be later described. The reciprocation of the brushes to cause them alternately to dip in the solvent and to press against the under side of the sole is effected by means of cams 42 on the cam shaft 22. These cams, as illustrated, are designed to press the brushes firmly enough against the work to cause the bristles to spread slightly. These cams 42 operate upon cam levers 44 pivoted at 46 upon the front of the frame 10 and connected by rods 48 to rock levers 50 journaled on the cross shaft 16 and joined by links 52 to the brush carriers 35 which are slidable on

30 35 40 45 50 55

Brushes 32 and 34, which are shaped as shown in Fig. 2 and are secured to carriers 35, are mounted for vertical reciprocation upon guide rods 36 into and out of coating material contained within the receptacle and into contact with the lower face of the work. The size of the brushes and their rate of reciprocation is so related to the rate of feeding movement of the work that the applied splotches of coating material overlap somewhat. Two of these rods 36 are provided which are held in sockets 38 at the bottom of the receptacle by means of clamp screws 40 and the upper ends of the rods are secured in spaced relation in a manner to be later described. The reciprocation of the brushes to cause them alternately to dip in the solvent and to press against the under side of the sole is effected by means of cams 42 on the cam shaft 22. These cams, as illustrated, are designed to press the brushes firmly enough against the work to cause the bristles to spread slightly. These cams 42 operate upon cam levers 44 pivoted at 46 upon the front of the frame 10 and connected by rods 48 to rock levers 50 journaled on the cross shaft 16 and joined by links 52 to the brush carriers 35 which are slidable on

the rods 36. It follows then that, during the use of the machine, solvent will be applied alternately by the brushes 32 and 34 to the under side of the sole carried past the brushes and maintained in contact with gage members 54 and 56 (Fig. 2) which are adjustably held on the rods 36 by screws 55. It will be understood, however, that the brushes form only one of a variety of operating tools which may be used to treat the work.

10 Feeding movement of the work to cause it to traverse the operating tool is effected first by means of toothed arcuate feeding members 60, 62, (Fig. 5) engaging the under surface of the work. These feeding members 60, 62 are complementary and each is substantially half a circle. The member 62 is formed directly upon the end of a shaft 64 which is positioned within a sleeve 66 carrying the other member 60 and this sleeve is journaled in an arm 68, the upper half of which is integral with the cover 12 and the lower half of which is removably held in position by screws 70 (Fig. 4). Rotation of these feeding members is effected from a long pinion 72 journaled in the cover 12 and driven through miter gears 74 (Fig. 2) from the drive shaft 14. The shaft 64 has fastened to it a pinion 76 meshing with the long pinion 72, while the surrounding sleeve 66 has fastened to it a pinion 78 also meshing with the long pinion 72. The two arcuate members 60, 62 engage the work successively to effect a forward movement thereof and each of them is mounted for axial movement under the control of springs 88, 98 tending to return them to their original positions. To this end a collar 80 with spaced flanges is attached to the pinion 76 and the shaft 64 and this collar 80 receives a roll 81 upon the end of a bell-crank 82 which is pivoted upon the top of the cover and the other end of which supports a roll 83 which is received between the flanges of a collar 84, slideable upon a rod 86. This collar has bushings between it and the rod 86 and is acted upon equally and oppositely by the springs 88 which press against the enlarged ends of the bushings. The rod 86 is positioned in lugs 90 integral with the cover 12 and is held therein by a set screw 92. Provision is thus made for movement of the arcuate feeding member 62 either toward or away from the gages 54, 56 when displaced axially by reason of the turning movement of the irregularly shaped sole S with which the feeding member 62 is in engagement. The return of the feeding member 62 to normal position will take place as soon as the member has disengaged the work. Similar apparatus is provided to effect the return to normal position of the associated feeding member 60, this apparatus comprising a flanged collar 94 integral with the sleeve 66, a bell-crank 96 and springs 98 upon a rod 99.

60 It will be seen by reference to Fig. 2 that the arm 68 has fingers 100 extending forwardly and outwardly from the end of the arm and that these fingers serve as supports for the upper end of the guide rods 36 upon which the brush carriers reciprocate. Secured to the fingers 100 as by screw pins 55 are the sector shaped gages 54 and 56 and upon the upper face of each gage is held a flat spring 102. These springs rest against the upper face of the work and assist in holding it in engagement with the arcuate feeding members 60, 62.

70 In order that the work may be held automatically in contact with the edge gages as it is fed forward, the feeding mechanism embodies another set of members 110 and 112, serving as

driven auxiliary feed rolls, each of which comprises a series of arcuate faces 114 for frictionally engaging the work intermittently. The rolls 110, 112 may be of rubber or may be faced with rubber or the like to increase their drag upon the work. The operative faces of these members 110, 112 are staggered so that the effect upon the work is substantially continuous and as the members are driven in the direction of the arrow in Fig. 4 they assist the feeding by tending always to hold the sole S in contact with the edge gages 54, 56. These members 110, 112 are slidably secured to a jack shaft 116 which is carried in the outer end of a cover 120 having hubs 122 (Fig. 6) which are pivotally mounted upon the cross shaft 16. Rotation of the jack shaft 116 is effected, by means of pinions 124 outside the cover and a series of pinions 126 within the cover, from the cross shaft 16. Since this cover is pivotally mounted on the cross shaft 16, it may be raised for inspection or repair of the associated parts and the feeding members 110, 112 are held frictionally by the weight of the cover and pinions in contact with the upper side of the work. In view of the fact that these members are moving transversely of the direction of forward movement, the arrangement is made such that each one can move axially along the jack shaft 116 with the work until the particular arcuate section which engages the work passes out of contact therewith, whereupon these members are returned to normal position by springs 128 and 130. The feeding member 110 is positioned beside a collar 132 secured to the jack shaft 116 and is slideable with respect to the jack shaft along a pin 134 extending into this collar. The collar serves as a stop to determine the normal position of the member 110 when returned by the spring 128. On the other hand, the feeding member 112 is mounted upon a sleeve 136 surrounding a portion of the collar 132 and the spring 130, one end of this sleeve being splined to the jack shaft 116 (Fig. 7). The normal position of the feeding member 112 is determined by engagement of the end of the sleeve 136 with a portion 138 of the cover 120 as said sleeve 136 is acted upon by the spring 130. The limit of downward movement of the cover 120, to avoid soiling of the auxiliary feed rolls by the brushes or other damage, may be adjustably determined by a stop screw 140 (Figs. 1 and 2) which is secured near the outer end of the arm 68 and is held in adjusted position therein by means of a lock nut.

It will be seen, therefore, that, in the use of the machine, each of the auxiliary feeding members 110, 112 acts successively upon the work by frictional engagement to urge the work into contact with the edge gages 54, 56. Forward progress of the work is being effected by the toothed feeding members 60, 62 to carry the work past the operating tools 32, 34. As an operative portion of a member 110 or 112 engages the work to urge it against the edge gages, said member is carried along with the work by friction a short distance in opposition to one of the springs 128 or 130 and then as soon as it disengages the work is carried back into normal position by a spring 128 or 130 ready for reengagement with the work at a point adjacent to the feeding members 60, 62 and the edge gages 54, 56.

A machine has, therefore, been provided by means of which the whole contour of a piece of work such as a shoe sole will be presented automatically to an operating tool without damaging

the work, without deviation from the desired path of movement, and without wear upon the machine. Since the toothed members 60, 62 engage the work intermittently and are axially 5 yieldable, there will be no tendency either to mar the work or wear the feeding members or to hold the work away from the edge gages. Similarly, the arrangement of the auxiliary feeding members 110, 112 is such that there is no 10 tendency to retard the forward feeding movement of the work or to cause an undue amount of slipping movement between these arcuate members and the work.

Having thus described my invention, what I 15 claim as new and desire to secure by Letters Patent of the United States is:

1. In a machine for operating upon shoe parts, the combination with operating means of a member movable to advance a piece of work 20 for the operation upon it, a work gage, and a member movable to urge the work toward the gage, one of said members being movable by the work in a plane substantially parallel to the surface of the work and in a direction transverse 25 to the active movement of the member.

2. In a machine for operating upon shoe parts, the combination with operating means of a member movable to advance a piece of work for the operation upon it, a work gage, and a 30 member movable to urge the work toward the gage, both of said members being movable by the work in a direction transverse to their active movements.

3. In a machine for operating upon shoe parts, the combination with operating means of a rotatable member movable to advance a piece 35 of work for the operation upon it, a work gage, and a rotatable member movable to urge the work toward the gage, said members being 40 mounted for axial movement by the work in a direction transverse to their active movements.

4. In a machine for operating upon shoe parts, an operating tool, and a driven feeding member 45 engaging the work intermittently and constructed and arranged to feed the work, said feeding member being mounted for displacement by the work laterally of the direction of feeding movement.

5. In a machine for operating upon shoe parts, 50 an operating tool, a driven feeding member engaging the work intermittently and constructed and arranged to feed the work forwardly, said feeding member being mounted for displacement by the work laterally of the direction of feeding movement, and means to restore to normal position said displaceable member during 55 periods of disengagement of the member with the work.

6. In a machine for operating upon shoe parts, 60 an operating tool, and means for moving the shoe part past the tool, comprising a plurality of members operable for successive engagement with the shoe part, said members being mounted for yielding movement laterally of the margin of the shoe part and being driven to impart a forward feeding movement thereto.

7. In a machine for operating upon shoe parts, 65 an operating tool, and means for carrying the shoe part past said tool, comprising rotatable driven members adapted to act successively upon the work to move it forward, one of said members being mounted for axial movement.

8. In a machine for operating upon shoe parts, 70 an operating tool, driven members for carrying the work past the tool and arranged to act suc-

cessively upon the work, said members being mounted for movement laterally of the direction of progress of the work, and means for returning to a normal position that one of the members which is not in engagement with the work. 5

9. In a machine for operating upon shoe parts having a curved contour, a tool for operating progressively upon the work, an edge gage adjacent said tool, and means for carrying the work past said tool in contact with the edge gage, 10 comprising a member mounted for forward feeding movement and for lateral movement toward or away from the edge gage and means for driving said member positively to move the work past the edge gage and for moving the member 15 impositively in a direction laterally of the direction of progress.

10. In a machine for operating upon shoe parts having a curved contour, an operating tool, and means for moving the work with respect to 20 the tool, comprising successively acting arcuate members, means for rotating said members to cause them to act successively upon the work, the members being mounted for axial movement, and means for returning a member to normal 25 position when it is out of contact with the work in case it has become displaced by the work.

11. In a machine for operating upon shoe parts, an operating tool, gaging means positioned adjacent thereto, and means for feeding the 30 work past said tool in contact with said gaging means, comprising coaxial arcuate members adapted to engage the work successively, means for rotating said members about their axes, and resilient means for moving said members along 35 said axes during periods of disengagement with the work.

12. In a machine for operating upon shoe parts, an operating tool, an edge gage adjacent thereto, and means for moving a shoe part to 40 carry it past said tool in contact with the edge gage, comprising plural rotatable means one of which operates to impart movement past the gage and the other of which operates to impart movement laterally toward the gage, one of said 45 rotatable means comprising arcuate portions adapted to operate upon the shoe part successively and yieldable with the moving shoe part to prevent dragging thereof across the shoe part. 50

13. In a machine for operating upon shoe parts, an operating tool, an edge gage adjacent thereto, and means for carrying the margin of the shoe part past the operating tool with the shoe part in contact with the edge gage, comprising laterally displaceable toothed members 55 for engaging the flesh surface of the shoe part and a friction member for engaging the grain surface of the shoe part.

14. In a machine for operating upon shoe parts, an operating tool, an edge gage adjacent 60 thereto, and means for carrying the margin of the shoe part past the operating tool with the shoe part in contact with the edge gage, comprising driven means for effecting forward feeding movement of the shoe part and frictional means having a slipping engagement with the shoe part tending to maintain it against the edge gage, said frictional means being yieldable 65 in the direction of feeding movement. 70

15. In a machine for operating upon shoe parts, an operating tool, an edge gage adjacent thereto, and means for carrying the margin of the shoe part past the operating tool with the shoe part in contact with the edge gage, comprising successively acting arcuate members pos- 75

itively driven to feed the shoe part forward and yieldably mounted to move laterally with the shoe part and friction means for holding the shoe part against the edge gage.

- 5 16. In a machine for operating upon shoe parts, an operating tool, an edge gage adjacent thereto, and means for carrying the margin of the shoe part past the operating tool with the shoe part in contact with the edge gage, comprising coaxial arcuate members positively driven to feed the shoe part and mounted for axial movement away from normal position and means for returning said members to normal position when they are out of contact with the shoe part.
- 10 17. In a machine for operating upon shoe parts, an operating tool, an edge gage adjacent thereto, and means for carrying the margin of the shoe part past the operating tool with the shoe part in contact with the edge gage, comprising coaxial arcuate members for moving the shoe part toward the edge gage, said members being mounted for yieldable movement with the shoe part as it goes forward.
- 15 18. In a machine for operating upon shoe parts, an operating tool, an edge gage adjacent thereto, and means for carrying the margin of the shoe part past the operating tool with the shoe part in contact with the edge gage, comprising two sets of coaxial cooperating arcuate members one of which sets causes forward movement of the shoe part and the other of which sets causes lateral movement of the shoe part, one set of said members being provided with

yieldable means acting to return a member to normal position after it has been displaced to either side of its normal position.

19. In a machine for operating upon shoe parts, an operating tool, an edge gage adjacent thereto, and means for carrying the margin of the shoe part past the operating tool with the shoe part in contact with the edge gage, comprising sets of coaxial cooperating arcuate members mounted for axial movement, one set of said members operating to effect forward movement of the shoe part and the other set operating to urge the shoe part toward the edge gage, and yieldable means permitting axial movement of the members of the latter set in the direction of forward movement of the shoe part and operating to return said members to normal position when they are out of contact with the shoe part.

20 20. In a machine for operating upon shoe parts, a work-supporting feed roll driven to cause a forward movement of the shoe part, an edge gage adjacent thereto, an operating tool to treat that face of the shoe part which is in engagement with said feed roll, a pivotal support, and an auxiliary feed roll journaled in said pivotal support for engagement with the other face of the shoe part, said auxiliary feed roll extending transversely to the line of forward movement and driven to tend to move the work laterally of the forward movement thereof, thereby to hold it in engagement with the edge gage.

ERASTUS E. WINKLEY.
